(57) **CLAIM**

The ornamental design for a knife and badge holder, as shown and described.

DESCRIPTION

FIG. 1 is a perspective view of a knife and badge holder showing our new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a bottom plan view thereof; and,

FIG. 7 is a top plan view thereof.

The dashed lines shown in FIGS. 1, 2, 3 and 7 represent stitching. These dashed lines form part of the claimed design.

The “dashed dot dot” line showing of a knife blade forms no part of the claimed design.
